UNITED STATES PATENT OFFICE.

GEORGE WASHINGTON WRIGHT, OF YOAKUM, TEXAS.

TONGUE-SUPPORT.

SPECIFICATION forming part of Letters Patent No. 643,736, dated February 20, 1900.

Application filed July 15, 1899. Serial No. 724,022. (No model.)

To all whom it may concern:

Be it known that I, GEORGE WASHINGTON WRIGHT, a citizen of the United States, residing at Yoakum, in the county of De Witt 5 and State of Texas, have invented a new and useful Tongue-Support, of which the following is a specification.

This invention relates to tongue-supports for vehicles, and has for its object to provide 10 a detachable device which may be fitted to the running-gear of any vehicle without changing the construction thereof.

To this end the present invention consists in the combination and arrangement of parts, 15 as will be hereinafter more fully described, shown in the accompanying drawings, and particularly pointed out in the appended claim, it being understood that changes in the form, proportion, size, and the minor de- 20 tails of construction may be made within the scope of the appended claim without departing from the spirit or sacrificing any of the advantages of the present invention.

In the drawings, Figure 1 is a top plan view 25 of a portion of the running-gear of a vehicle having the present invention applied thereto. Fig. 2 is a longitudinal sectional view thereof. Fig. 3 is a detail perspective view of the improved tongue-support.

30 Corresponding parts in the several figures of the drawings are designated by like characters of reference.

Referring particularly to Fig. 3 of the drawings, it will be seen that the device comprises 35 a flat metallic plate 1, preferably rectangular in form and provided with a central opening 2. The respective rear corners of the plate are each provided with an opening 3, in which is connected a link of a chain-section 4, the 40 rear ends of the chain-sections being connected together by a suitable ring 5. The opposite forward corners of the plate are also provided with openings 6, in which are engaged the hooks 7 of the respective coiled springs 8, 45 which have their forward ends provided with suitable hooks 9 for engagement with a flat triangular plate 10. The base of the triangular plate is arranged adjacent to the forward ends of the springs, and the hooks 9 of 50 the latter are fitted in openings 11, provided through the plate at the opposite rear corners thereof.

Arranged longitudinally in front of the triangular plate is a rod 12, having its rear end provided with a hook or link 13, which is engaged in an opening 14, provided through the apex of the triangular plate. 55

The application of the device will be best understood by reference to Figs. 1 and 2 of the accompanying drawings, in which have 60 been illustrated an axle 15, a bolster 16, located above the axle, and a reach-bar 17, having its forward end arranged between the axle and the bolster, and pivotally connected thereto by the usual king-bolt 18, extending forwardly 65 from the axle 15, are the usual hounds 19, between the forward ends of which is pivoted the tongue 20, upon a suitable transverse pivot-bolt 21, extending through the opposite hounds and the rear end of the tongue. 70

In applying the present device the rectangular anchor-plate is placed upon the top of the bolster 16 and the king-bolt 18 is positioned through the opening 2 of the plate, whereby the latter is held in a relatively- 75 fixed position upon the bolster. The convergent chains 4 extend rearwardly from the anchor-plate, and the ring 5 is engaged with a suitable hook 22, provided upon the upper side of the reach. The springs 8 and the rod 12 extend longitudinally in front of the bolster, and the forward end of said rod is provided with a ring or hook 23 for engagement with a suitable hook 24, provided upon the upper side of the tongue and in advance of 80 the pivotal point thereof. Thus it will be seen that the rear end of the device is fixed to the reach 17 and the forward end thereof is fixed to the tongue in advance of the pivotal point thereof, the intermediate portion of 85 the device extending over the top of the bolster, whereby the forward end of the tongue is normally maintained in an elevated position, and the springs 8 provide for the required flexibility, whereby the outer end of 90 the tongue is free to rise and fall with the movement of the draft-animals.

From the foregoing description it will be seen that the present device may be readily fitted to vehicles of various forms without 95 changing or altering the construction thereof. Furthermore, the several parts of the device are flexibly connected together, so that they may give with the movement of the vehicle

and thereby prevent binding of any of the parts. At the same time the device is normally maintained in its operative position, so that the tongue is always supported in the proper manner.

It will be noted that the chains 4 and the springs 8 are connected to the plate 1 at opposite sides of the central opening therein, which prevents twisting or turning of the middle portion of the support, so as to obviate displacement of the latter and maintain a straight pull or tension upon the tongue.

What I claim is—

In a tongue-support, the combination with a flat plate having a central opening therein, and receiving the king-bolt of the vehicle, of a pair of chains connected to the rear end of the plate and at opposite sides of the opening therein, convergent rearwardly therefrom, and detachably connected at their point of

convergence to the reach-bar of the vehicle, a pair of springs connected to the forward portion of the plate, and at opposite sides of the opening therein, a triangular plate having the forward ends of the springs connected to the opposite rear corners of the plate, and a rod loosely connected to the forward end or vertex of the plate, extending forward therefrom, and detachably connected at its forward end to the tongue, in advance of the pivotal point of the latter, substantially as and for the purpose set forth.

In testimony that I claim the foregoing as my own I have hereto affixed my signature in the presence of two witnesses.

GEORGE WASHINGTON X WRIGHT.
